(57) **CLAIM**

The ornamental design for motor valve, as shown and described.

DESCRIPTION

FIG. 1 is a first perspective view of a motor valve showing our new design;

FIG. 2 is a second perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines depict portions of the motor valve that form no part of claimed design.
